METHOD OF MAKING BAGS

Albert Butterfield, Middletown, Ohio, assignor to
Advance Bag and Paper Company, Incorporated,
Boston, Mass., a corporation of Maine

Application June 12, 1933, Serial No. 675,442

6 Claims. (Cl. 93—35)

This application relates to a method of making bags of the kind popularly known as shopping bags. Such bags are usually made of tough, strong paper, and while throughout this application for a patent I shall refer to them as paper bags, it is not to be understood that other material may not be used in their manufacture.

A particular feature of this bag resides in its being strengthened by a broad vertical zone extending down the center of its front and rear wall, wherein the paper is of double-thickness. The handles for carrying the bag are secured in these zones and the zones continue down into the folds which constitute the bottom of the bag, thereby giving the bag great strength. My invention resides in a method of making bags of this type.

Referring now to the drawings.

Fig. 1 is an elevational view of one of these bags, which is finished save that the bottom is only partially folded and the handles are yet to be attached;

Fig. 2 is a tube made from two pieces of paper, these pieces of paper being pasted together with wide seams in the middle of the front and back walls of the bag, which makes a substantial part of the front and back double;

Fig. 3 shows a complete bag;

Fig. 4 is a portion of a side elevation of a machine that I may employ in the practice of my method of making these bags, and

Fig. 5 is an end elevation of this machine.

Figs. 4 and 5 are principally diagrammatic.

I shall now describe the bag, with the assistance of Figs. 1, 2 and 3 of the drawings. Fig. 2 illustrates the body 10 of the bag, which comprises two similar halves, A and B. It will be noticed that the parts A and B overlap and are pasted together to form a broad zone 11 of double thickness in the middle of the front and back. In Fig. 1 the upper edge of the body has been folded inward at 12, forming a hem, and the lower end of the body or tube 10 has been partially folded to form the bottom of the bag, shown complete, in Fig. 3. Finally, handles 13—13, made of heavy cord, are secured to the upper end of the bag, the ends of the cords being tucked into holes 14—14 that are pierced near the edges of the double-thick zones 10 during the process of making the bag.

As will be readily understood, the double-thick zones 11 add very much to the strength of the bag. At the upper end the double-thick zones are folded into the hem, and the handles 13—13 are secured to the bag by staples that

are clinched in the double-thick zones. At the lower end these double-thick zones are folded into the structure that forms the bottom of the bag, see Fig. 1, and finally pasted together in overlapping relationship, as in Fig. 3, producing a structure of remarkable strength.

I shall now describe a portion of the bag-making machine which I may use in carrying out my method of making bags, referring to Figs. 4 and 5. Inasmuch as Figs. 4 and 5 are diagrammatic I shall refrain from describing structural details of the machine, assuming that these will be understood.

A roll or web of paper, A, is mounted at 20. Paper from this web is guided by a roller 21 to a uniting roller 22, around which the web is carried and from which it runs to an idler roller 23. Mounted adjacent to the roller 22 is a paste-applying device, whereby the outer surface of the web is served with paste as it rounds the roller 22, as will be more fully explained presently.

A second roll or web of paper, B, is mounted at 25. Paper from this web is guided by a roller 26 across the roller 22, and it too runs to the idler 23. Referring to Fig. 5 it will be seen that the rolls of paper, A and B respectively, are off-set with reference to each other, but overlap a distance equal to the width of the double-thick zones 11 of the bag. The paste-applying device previously referred to comprises a pan 27 containing paste, and a series of paste-applying wheels 28. These wheels dip into the paste in the pan 27 and by suitable means, not shown, they are pressed against the web A as it rounds the roller 22, thereby applying paste to the paper in this overlapping zone. When the web B comes in contact with the paste-coated surface of A the webs are united, pasted together, and together they round the roller 23 and thereafter round the roller 24 as a unit. From the roller 24 the combined webs pass to an ordinary bag-making machine, which is not shown.

The portion of the bag-making machine not shown being old and well known in the art it is deemed unnecessary to illustrate or describe it. It will therefore suffice to say that it contains means whereby the combined webs A and B are drawn around the roller 24 and into the mechanism for making the bags. It is obvious therefore that the webs are under considerable tension from the time they leave their respective rolls A and B. This tension presses the overlapping thickness of web together as the web is 110

drawn around the rollers 22, 23 and 24, thereby pressing the paste into the paper and insuring a good union between the webs.

The next step in my method is to join the free edges of the web A-B with a lap seam of the same width as that which joins the webs A and B. This step begins with applying a zone of paste to the free edge of the web A as it rounds the roller 24. For this purpose I employ a second paste-applying device 30, similar to the one previously described. This is contiguous to the roller 24 and its wheels 28 apply paste to the web A in the manner described. Next each of webs A and B is folded longitudinally with a fold intermediate its respective edges, the edge of web A being kept outside the edge of web B, thereby bringing the paste-bearing surface of web A into contact with the surface of web B, forming a second seam having a width equal to the width of zones 11. Thus a continuous tube is formed, which tube is cut into pieces such as is seen in Fig. 2, each suitable for forming one bag.

Various means may be employed in completing the bag, including doing it by hand. But I prefer to employ an ordinary bag-making machine. It is not essential that the paste be applied in a series of narrow stripes, for if desired it may be applied in a single stripe co-extensive in width with the zone. I have mentioned staples as a means for securing the handles to the bags, but other means may be employed, cement for instance.

I claim:

26. 1. The method of making bags, which method comprises pulling a web of paper past a given point, simultaneously applying adhesive to a broad longitudinal zone of said web, beginning at one edge, pulling a second web of like paper past said point in parallelism with and overlapping the adhesive-carrying zone of the first web, joining said webs; applying a broad longitudinal zone of adhesive to the free edge and on the same side of the first web as before, folding both webs longitudinally intermediate their respective edges and uniting said adhesive-carrying free edge of the first web to the free edge of the second web, thereby forming said webs into a tube.
27. 2. The method of making bags, which method comprises pulling a web of paper past a given point, simultaneously applying adhesive to a broad longitudinal zone of said web, beginning at one edge, pulling a second web of like paper past said point in parallelism with and overlapping the adhesive-carrying zone of the first web, thereby joining said webs; applying a longitudinal zone of adhesive to the free edge and on the same side of the first web as before, folding both webs longitudinally intermediate their respective edges and uniting said adhesive-carrying free edge of the first web to the free edge of the second web, thereby forming said webs into a tube, then cutting the tube into lengths making the lengths into bags in the usual way.
28. 3. The method of making bags, which method comprises pulling a web of paper past a given

point and simultaneously applying adhesive to a broad longitudinal zone of the web, beginning at one edge, pulling a second web of like paper past said point in parallelism with and overlapping the adhesive-carrying zone of the first web, thereby joining said webs; applying a longitudinal zone of adhesive to the free edge of said first web, on the same side as before, folding both webs longitudinally intermediate their respective edges and uniting said adhesive-carrying free edge of the first web to the free edge of the second web, thereby converting said webs into a tube, cutting said tube into bag lengths and forming said lengths into bags.

4. The method of continuously making paper bags of the kind wherein a broad vertical zone of each side wall is composed of two thicknesses of paper, which method comprises moving a web of paper longitudinally past a given point, simultaneously applying adhesive in a longitudinal zone beginning at one edge thereof, the width of which zone equals the width of said zones of double thickness, moving a second web in parallelism with and overlapping said adhesive-carrying zone of the first web, joining the webs, thereby forming a wide web with a broad double-thick zone in the center, applying a longitudinal zone of adhesive, as broad as the first, at the remaining free edge of the first web, folding both webs longitudinally intermediate their respective edges and overlaying said adhesive-carrying zone with the free edge of the second web, thereby forming a continuous flat tube, each side wall whereof has the required zone of double thickness, which tube is cut into lengths and made into bags.

5. The method of making paper bags wherein broad double-thick vertical zones are formed in the front and rear walls by overlapping the paper, which method comprises moving a web of paper longitudinally past a given point, at said point applying adhesive in a longitudinal zone extending to one edge thereof, said zone having a width corresponding to said double-thick zones, moving a second web in parallelism with and overlapping the first a distance equal to the width of said zone, joining said webs by means of said applied adhesive, folding both webs longitudinally intermediate their respective edges, uniting the overlapping edges with adhesive, cutting the tube thus formed into one-bag lengths, and making each length into a bag.

6. The method of making paper bags, which method comprises moving a web of paper past a given point, applying paste thereto in a longitudinal zone of definite width and beginning at one edge of the web, moving a second web in parallelism with and overlapping the first a distance equal to the width of said paste-carrying zone, the width of the second web equalling that of the first, joining the webs with said coating of paste, folding both webs longitudinally intermediate their respective edges, pasting the overlapping parts of the webs together to form a tube, cutting the tube into one-bag lengths and forming each length into a bag.

ALBERT BUTTERFIELD.
